UNITED STATES PATENT OFFICE.

ALFRED J. FLAUDER, OF BRIDGEPORT, CONNECTICUT, ASSIGNOR TO THE WEIDLICH BROS. MFG. CO., OF BRIDGEPORT, CONNECTICUT, A CORPORATION OF CONNECTICUT.

DESIGN FOR A CRUET STAND.

Application filed September 30, 1927. Serial No. 23,579. Term of patent 7 years.

To all whom it may concern:

Be it known that I, ALFRED J. FLAUDER, a citizen of the United States, and a resident of Bridgeport, in the county of Fairfield and State of Connecticut, have invented a new, original, and ornamental Design for a Cruet Stand, of which the following is a specification, reference being had to the accompanying drawing, forming a part there-

of, which is a perspective view of the article showing my new design.

I claim:

The ornamental design for a cruet stand substantially as shown.

Signed at Bridgeport, in the county of Fairfield and State of Connecticut, this 28 day of September, 1927, A. D.

ALFRED J. FLAUDER.
